D. C. BRANDON

DEPHLEGMATOR

Filed July 19, 1922

Inventor
D. C. Brandon,
By Marks Clark
Atty.

UNITED STATES PATENT OFFICE.

DAVID CHARLES BRANDON, OF BALIKPAPAN, BORNEO, DUTCH EAST INDIES.

DEPHLEGMATOR.

Application filed July 19, 1922. Serial No. 576,103.

To all whom it may concern:

Be it known that I, DAVID CHARLES BRANDON, residing at Balikpapan, Borneo, Dutch East Indies, have invented certain new and useful Improvements in Dephlegmators, of which the following is a specification.

With the dephlegmators hitherto known it is very difficult to obtain the so-called "straight run" gasoline from crude oils containing water. The production of "straight run" gasoline decreases in proportion to the increase of the water content of the crude oil to be treated, and the products requiring redistillation increase quickly, which causes the capacity of the manufacture to be diminished, for the stills which could be used for other purposes have now to serve as redistillate stills. Obviously the fuel consumption will also increase, while also the large stock of gasoline requiring redistillation will constitute a great danger to the refinery.

The dephlegmator according to this invention possesses the following advantages over similar apparatus already known.

1. All the parts subjected to incrustation or breakage are easily accessible without dismantling the apparatus.
2. The composition of the distillates produced can for each compartment of the apparatus be regulated exactly and very simply by means of steam and watertaps arranged on the apparatus.

The dephlegmator according to my invention comprises a vertical column provided with two or more superimposed horizontal cooling compartments separated by vapor chambers adapted to be heated, the said cooling compartments preferably consisting of groups of pipes closed at their outer ends by removable covers or headers extending from the column. These headers or covers are provided with inlet and outlet conduits for the cooling liquid and the vapor chambers between the cooling compartments are provided with baffle plates through or around which the vapors can pass in their upward travel. In a preferred embodiment the baffle plates are provided with tube shaped vapor outlets, the openings being above the outlets for the condensates formed in the vapor chambers.

My invention will be more readily understood if reference is made to the accompanying drawings which illustrate an embodiment thereof.

In the drawings, wherein similar reference numbers indicate identical parts, Fig. 1 is a vertical section of the dephlegmator while Fig. 2 is a vertical section along the line II-II of Fig. 1.

The apparatus comprises a vertical column divided into superimposed chambers *a*, *b*, *c*, *d* and *e*. Of these, the chamber *a* consists of a horizontal cooling compartment 1, which crosses the part 2, 3 of the vertical column.

The cooling compartment 1 is formed by cooling pipes mounted in the perforated pipe-plates 4 and 5. These pipe plates are covered by the removable arched covers 6 and 7 which extend from the column. In the cover 6, which is provided with a horizontal baffle plate, two openings 8 and 9 are provided which serve for the inlet and the outlet of the cooling medium. The uppermost end 2 of the vertical column is closed by a dome, which has a central tube 11, provided with a flange for attachment to a cooler.

The compartment *b* comprises a vertical cylinder 12, provided at both ends with flange rings for connecting to the vertical cylinder pieces of the compartments *a*, *c* respectively.

Between the compartments *a* and *b*, a sheet iron plate 13 is arranged, from which a dish 14 is suspended by bolts. The plate 13 has in the middle an aperture 15 through which the vapors can pass to the cooling chamber 1, and in the dish 14 four smaller apertures 16 are made to this end, preferably close to the edge of this dish.

Lower down in the wall of the compartment *b* two branch pipes 17 and 18 are arranged, which are provided with screw couplings to which a double ring-shaped steam conductor is connected. In the same wall a tube 19 is provided for removing the condensates to the cooler.

Between the compartments *b* and *c*, an imperforate plate 20 is arranged which in the middle possesses an open vertical pipe 21 through which the vapors pass from compartment *c* to compartment *b*.

The compartment *c* is similar to the compartment *a*. The compartment *d* forming the lower part of the vertical column, is provided with a flanged tube 23 for connecting a separator used for removing the liquid from the vapors coming from the still. A plate 24 with central opening 25 is arranged between the compartments *c* and *d*.

The compartment *e* serves as a base for the dephlegmator, and according to a preferred embodiment of my invention this compartment is provided in the middle with an inverted U-shaped pipe 26, which at its outer end is provided with a flange 27, the latter being connected with an outlet pipe for leading heavy condensate to a cooler. Furthermore, two pipes 28 and 29 are present which are connected with a double ring-shaped steam conductor, this latter being positioned above the point 37 of the tube 26, the reason for this arrangement being hereinafter explained. The other end 36 of the U-shaped tube 26 is open and terminates inside the dephlegmator, whilst on the curve of the said tube is arranged an upward hollow projection 35.

Separating the compartments *d* and *e* is a plate 38 having a conical or flared plate 30 attached thereto, the diameter of this latter being smaller than that of the dephlegmator column so that vapors formed in the compartment *e*, as will be hereinafter described, may ascend between the edge of this plate and the walls of the column. In order to allow these vapors to pass from the compartment *e*, holes 34 are provided in the plate 38.

30 The improved dephlegmator works as follows:

The vapors from a still after passing through a separator for removing the liquid from the vapors, enter the dephlegmator at 35 23. Passing through the opening 25 in the plate 24 they reach the undermost row of pipes in the cooling compartment *c* where their flow is interrupted by each pipe. The condensates fall from the uppermost pipes 40 on to those arranged beneath, so that the vapors are not only divided into different streams, but also continue their way through a rain of condensates. The working is more efficient than with coolers 45 hitherto known because there are no baffle-plates, thus enabling the vapors to come into close contact with the cooling surfaces. Attention must be paid to the fact that the vapors which escape through the central 50 aperture 25 are inclined to follow the way with the smallest resistance. The number of tubes to be passed at the sides being less than at the middle, the vapors could rise along the side portions of the compartment 55 *c*. This is, however, prevented by the baffles 33 (see Figure 2), the most efficient spacing of which can be determined by experiment.

The heavier vapors formed by the heavy 60 oil gases and steam condense in this cooler and fall back on the plate 24 and through the opening 25 to the dish 30 and further through the pipes 31 and 32 to the bottom of the dephlegmator. The condensates 65 having arrived at the bottom, the oil will

float upon the water so that on the water in the curved open leg of the U-shaped tube 26 there is a thin film of oil. In the curve of the tube is the opening 35 for the outlet of the condensate. The quantity of the 70 condensate becoming larger, the level of the water in the curved open leg will rise correspondingly, whereas the column of liquid outside will rise to a greater height, because always more oil will fall down upon the 75 water. Finally the mixture of oil and water will flow off through the U-shaped tube to a cooler.

The vapors which have passed the cooling compartment *c* arrive through the pipe 21 80 in the compartment *b* where they encounter the dish 14. Further they pass through the apertures in the dish 14 and the aperture in the plate 13 to the cooling compartment *a* which works in the same way as the cooling compartment *c*. The vapors, which are not condensed in the cooling compartment *a* pass through the outlet 11 to a siphon cooler.

The plate 20 does not possess apertures and can be considered as the bottom of the coolers with the exception of the lowermost cooler. The lightest substances of the condensate remaining therein can again be vaporized by means of steam. The condensate can pass through the outlet 19 to 95 a cooler.

By regulating the steam and watercocks the production of certain distillates can efficiently be controlled, e. g. by using a greater quantity of cooling water the 100 heavier substances of the mixture will condense, whereas from the distillate the lighter substances can be vaporized by indirect heating by means of steam. Thus the quality of the products can be controlled and the composition is subjected to the will of the distiller.

An important advantage of the application of the dephlegmators according to my invention consists in the economizing of 110 fuel because the quantity of redistillate gasoline is very small. The stills which are employed for the redistillate tanks can be put out of use, whereas less transfers are needed and in consequence the steam pumps 115 will consume less steam. The idle redistillate tanks may eventually be used for the treating of crude oil thus augmenting the capacity of the refinery. Although the dephlegmator described above is especially 120 adapted for still-batteries, it can also be used successfully for condensing the vapors provided by tube furnaces. In that case dephlegmators of simpler construction may be employed.

Having now particularly described and ascertained the nature of my said invention and in what manner the same is to be performed, I declare that what I claim is:

1. A dephlegmator including a vertical 125

- column having a vapor inlet at its lower end and a vapor outlet at its upper end, superposed cooling compartments arranged in said column and each having a group of superposed horizontally arranged tubes, means for introducing a cooling fluid into and discharging said fluid from said tubes, a combined vapor and condensate chamber arranged between said cooling compartments, the lower end of each cooling compartment being open to permit vapors rising in the column to contact with said tubes in their vertical movement and condensation formed by this cooling to be showered down on the vertically rising vapor, and means for heating the condensate deposited in the combined vapor and condensate chamber.
2. A dephlegmator as claimed in claim 1 in which the ends of the cooling compartments are provided with removable covers to facilitate the cleaning of said tubes.
3. A dephlegmator as claimed in claim 1 in which a plate is arranged between the combined vapor and condensate compartment and the upper one of said cooling compartments, said plate having an aperture to permit vapor from the combined vapor and condensate chamber to rise into the upper cooling compartment, and the condensate formed in the upper cooling compartment to flow downwardly into the combined vapor and condensate chamber.
4. A dephlegmator as claimed in claim 1 in which a horizontally disposed plate forms a partition between the upper cooling compartment and the combined vapor and condensate chamber, said partition being provided with an aperture to permit the passage of vapor and condensates, and a dish arranged below said plate and provided with apertures.
5. A dephlegmator as claimed in claim 1 in which the bottom of the combined vapor and condensate chamber is formed of a horizontally disposed plate having an upwardly projecting pipe to permit vapor from the lower cooling compartment to rise into the combined vapor and condensate chamber, said last mentioned chamber having a condensate outlet arranged below the upper end of said pipe.
6. A dephlegmator as claimed in claim 1 in which the lower portion of the column is provided with a dish having depending hollow legs extending downwardly into close proximity to the bottom of the column and adapted to convey condensates from the dish into the lower portion of the column, a substantially inverted U-shaped pipe extending through the bottom of the column and having an inlet leg arranged in close proximity to the bottom of the column, a hollow inlet projecting upwardly from the last mentioned pipe to permit condensates reaching a level above said last mentioned pipe to flow into the latter, and means for heating the lower portion of the column below said dish.

In testimony whereof I affix my signature.

DAVID CHARLES BRANDON.
